Attorney

UNITED STATES PATENT OFFICE.

HENRY J. FREY, OF PALMYRA, MISSOURI.

BOTTLE-STOPPER.

1,283,719.

Specification of Letters Patent. Patented Nov. 5, 1918.

Application filed August 18, 1917. Serial No. 186,960.

To all whom it may concern:

Be it known that I, HENRY J. FREY, a citizen of the United States, residing at Palmyra, in the county of Marion and State of Missouri, have invented new and useful Improvements in Bottle-Stoppers, of which the following is a specification.

This invention relates to improvements in stoppers for bottles and other containers, and particularly to a valved stopper designed for preventing, or deterring to a maximum degree, the refilling of the bottle after having once been filled and the stopper applied.

The object of the invention is to provide a valved stopper adapted to effectually subserve its intended purpose, and which can be made and sold at a reasonable cost.

The invention consists of the features of construction, combination and arrangement of parts hereinafter fully described, and claimed, reference being had to the accompanying drawing, in which:—

Figure 1 is a vertical longitudinal section through the upper portion of a bottle arranged in an upright position, showing the valved stopper applied and the valve in closed position.

Fig. 2 is a similar view of the bottle tilted for discharge of its contents.

Fig. 3 is a similar view of the bottle in inverted position.

Fig. 4 is a sectional plan view on line 4—4 of Fig. 1.

Fig. 5 is a vertical section on line 5—5 of Fig. 1.

Referring to the drawing, 1 designates the neck of a bottle or other container, within which is fitted a stopper 2 embodying the novel features of my invention. This stopper is made of any suitable material and is preferably tapered to tightly fit the neck 1, and is provided at its upper end with a flange 3 serving as a stop to limit its downward movement and prevent it from being forced down into the bottle.

Extending vertically through the stopper, and coaxially therewith, is a discharge tube 4, made of metal or other suitable material, said tube being provided with a lower open end 5 and formed in its diametrically opposite sides, between its lower end and the base

of the stopper 2, with inlet slots 6, for the flow into the tube of the liquid to be discharged from the bottle. The upper portion of the tube extends above the flange 3 of the stopper and terminates in an outlet 7 provided with a bent portion 8 of any suitable shape, which bent portion acts as a guard and forms a tortuous channel to prevent the introduction of an implement into the tube in an attempt to unseat the stopper valve, as hereinafter described.

The portion of the tube between the upper end of the stopper and the outlet 7 is extended to provide a spherical valve chamber 9, communicating at its upper end with the outlet 7 and at its lower end through a constricted port 10 with the body of the tube surrounded by the stopper. This chamber 9 is provided with a suitable inlet 11 for the admission of air in the discharge of the liquid from the bottle, and has arranged therein a valve 12. The valve 12 is provided with a curved or partially spherical base or seat portion 13, adapted when the valve is in closed position to rest upon a seat 14 formed by the base of the chamber 9, so as to close the passage 10 against the introduction of liquid. A suitable closure 15 is provided for sealing the upper end of the outlet 7 under normal conditions to prevent the access of dirt, dust and other foreign substances.

The valve 12 is provided with a depending stem 16 projecting downwardly into the body of the tube 4. This stem 16 is coupled by a flexible valve controlling connection 17 with a valve controlling weight 18, which connection 17 may be in the form of a chain, cable or the like. The weight 18 is provided with a conical upper end 19 projecting into the open end 5 of the tube and having at the base of its marginal portion an outwardly extending flange or shoulder 20. The conical portion 19 forms a guiding or centering and pivoting member, whereby the weight 18 is guided in its vertical movements, and is also permitted to tilt laterally in any direction on the lower end of the tube 4 as a fulcrum. The shoulder or flange 20 is adapted to abut against the lower end of the tube 4 to limit the upward movement of the weight and valve, and is preferably

curved or arranged at an acute angle to the conical surface 19 in order to permit the weight to have ease or freedom in its universal lateral movements.

5 A suitable anchoring or locking device is provided for holding the stopper locked within the bottle neck. This device, as shown, is preferably formed of spring wire bent to provide a pair of locking arms 21, 10 arranged to diverge in an upward direction and converge in a downward direction and having their converging ends united by an eye or coil 22. This eye or coil 22 is disposed in the lower end of the tube 4 in proximity 15 to the lower ends of the slots 6, and the arms 21 project outwardly through said slots with their outer free ends arranged to bear against the top of the body of the bottle, whereby said arms act as locking members 20 to hold the stopper against extraction. The locking device is secured in position within the tube by a retaining pin 23 which passes through the eye 22 and also through the sides of the tube 4 and may be fixed against 25 displacement in any suitable manner. The locking arms are arranged so as to fold inwardly so that they may be held, against their tendency to move outwardly, by the operator within the plane of the outer surface of the stopper 2 in the operation of introducing said stopper into the bottle neck, whereby when the stopper is fully inserted and the arms 21 released for movement the said arms will move outwardly under the 30 action of the spring coil 22 into engagement with the top of the bottle body, thereby locking the stopper against any possibility of removal.

It will be understood that in the operation 40 of discharging all or a portion of the contents of the bottle, the bottle is turned from the normal upright position shown in Fig. 1 to the inverted position shown in Fig. 3, in which operation the valve 12 and weight 45 18 will move downward or forward by gravity, thus unseating the valve for the discharge of the liquid from the bottle, air entering the bottle through the inlet 11 and tube 4 to take the place of the discharged liquid. When the bottle is again restored 50 to an upright position, the valve 12 will drop by its own weight, and the downward movement of the controlling weight 18, back to normal position and thus close the passage 55 10 against the introduction of liquid. If the bottle is laid horizontally or upon one of its sides in an attempt to cause the valve to open so the liquid can be forced or otherwise introduced into the bottle, the tendency 60 of the valve to move open by gravity will be counteracted by the weight 18, and in such action the weight 18 will tilt downwardly toward the lower side of the bottle and in so doing will draw upon the connection 17 and 65 thus move the valve 12 to closed position.

The valve 12 is made of some material which will give it sufficient weight to normally close by gravity, but which will adapt it to float in liquid, so that under some conditions the valve will float to closed position as soon 70 as an attempt is made to refill the bottle, thus preventing any attempt of this character.

It will be observed that the weight 18 has its body portion in the form of a double cone 75 frustum, with the reduced ends of the cone frustum arranged in apposition, the lower cone being the larger, thus making the base of the weight of maximum area, whereby the weight is adapted to easily tilt and close the 80 valve when the bottle is placed in a slanting, horizontal or upright position. Hence it will be seen that the valve 12 is always closed except when the bottle is turned vertically upside-down. In this position, however, no 85 liquid can be forced into the bottle because the pressure of the air in the bottle will prevent it. If, however, an attempt should be made to refill the bottle by heating the bottle to expand the air in it and then submerging and cooling the bottle to cause the air to contract and form a partial vacuum designed to effect the suction of liquid into the bottle, this will be prevented by reason 90 of the fact that the valve 12 will float in the 95 entering liquid and be forced by the liquid against its seat 14, thus preventing the liquid from entering the bottle, as will be readily understood.

It will thus be seen that the invention provides a stopper having a novel construction of valve controlled means designed to prevent the introduction of liquid, whereby the absolute prevention of the introduction of liquid will be effected or the operation of introducing a liquid rendered so slow and difficult as to make it practically impossible to refill the bottle with any degree of economy or within any reasonable time. Also it will be seen that the stopper is simple of construction and may be made and sold at a 110 comparatively low cost.

Having thus fully described my invention, I claim:

1. A closure for containers comprising a 115 stopper, a discharge tube extending through the stopper, said tube having a projecting inner end portion provided with inlet openings and a projecting outer end portion formed with a spherical valve chamber having an outlet, a combined float and gravity 120 valve disposed within said chamber and having a partly spherical surface to engage the same, said valve having a stem extending into said tube, a valve controlling weight 125 tiltably engaging the lower end of the tube, and a flexible connection extending through the tube and loosely connecting the weight with the valve stem.

2. A closure for containers comprising a 130

stopper, a discharge tube extending through the stopper, said tube having a lower inlet end and an upper outlet end, said inlet end being provided with diametrically opposed 5 air inlet apertures, valve mechanism controlling the flow of liquid through the tube, and a locking device mounted within the

apertured end of the tube and having reversely movable spring arms projecting outwardly through said apertures and adapted 10 for engagement with the bottle neck to lock the stopper from withdrawal.

In testimony whereof I affix my signature.
HENRY J. FREY.
